(57) CLAIM

The ornamental design for an earphones with case, as shown and described.

DESCRIPTION

1.1 : Front view of earphones with case.

1.2 : Rear view of earphones with case.

1.3 : Side view of earphones with case.

1.4 : Side view of earphones with case.

1.5 : Top view of earphones with case.

1.6 : Bottom view of earphones with case.

1.7 : Perspective view of earphones with case.

1.8 : Front view of earphones close up.

1.9 : Rear view of earphones close up.

1.10 : Side view of earphones close up.

1.11 : Side view of earphones close up.

1.12 : Top view of earphones close up.

1.13 : Bottom view of earphones close up.

1.14 : Perspective view of earphones close up.

1.15 : Front view of case close up.

1.16 : Rear view of case close up.

1.17 : Side view of case close up.

1.18 : Side view of case close up.

1.19 : Top view of case close up.

1.20 : Bottom view of case close up.

1.21 : Perspective view of case close up.

The broken lines in the drawings are for the purpose of illustrating portions of the earphone with case that form no part of the claimed design.
